UNITED STATES PATENT OFFICE.

CUMBERLAND MASSIE, OF LACLEDE COUNTY, MISSOURI.

HYDRAULIC ENGINE.

SPECIFICATION forming part of Letters Patent No. 244,639, dated July 19, 1881.

Application filed May 19, 1881. (No model.)

To all whom it may concern:

Be it known that I, CUMBERLAND MASSIE, a citizen of the United States, residing in the county of Laclede and State of Missouri, have 5 invented certain new and useful Improvements in Hydraulic Engines; and I do hereby declare the following to be a full, clear, and exact description of the invention, such as will enable others skilled in the art to which it 10 appertains to make and use the same, reference being had to the accompanying drawings, and to letters or figures of reference marked thereon, which form a part of this specification, and in which—

15 Figure 1 is a side elevation of my improved hydraulic engine, and Fig. 2 is a vertical transverse section thereof.

This invention relates to improvements in hydraulic engines of that class employing reciprocating buckets, which receive the water from above-arranged chutes and transmit a rotary motion to the driving-wheel which drives the machinery, its object being to simplify the construction and arrangement of the parts and 20 to obtain greater leverage or power of the water; and it consists in the combination, with the aforesaid parts, of reciprocating chutes, with their shaft, adapted by intermediate mechanism to operate in harmony with the action 25 of the reciprocating buckets, intermediate stationary chutes conducting the water to the buckets, while the reciprocating chutes receive the water from a stationary funnel or chute communicating with the sluice or water source, 30 substantially as hereinafter more fully set forth and claimed.

Referring to the accompanying drawings, A A indicate a rectangular horizontal frame, at one end of which is arranged and fastened 40 an upright similar frame, A'.

B is a shaft hung in the lower end of the upright frame, and having a disk, a, about at its center, and two arms, b, one arranged upon each side of said disk, which are connected by 45 the pitmen or rods c to the drive-wheel B', or rather to its crank-shaft d.

C C are two buckets secured at the outer ends of two arms or spokes, e, fastened to the periphery of the disk a, each arm standing at 50 about an obtuse angle with a horizontal plane passing through the disk when the buckets are in a balanced position, as clearly understood from the drawings.

D D are two reciprocating chutes, secured 55 upon a shaft, f, bearing in the upper ends of

two inner uprights of the frame A', with one end provided with a crank, f', connected by a short link, g, jointed to a longer lever, h, hung at h' between one of the inner and one of the outer uprights of the frame A'. The longer 60 arm of the lever h is jointed to a pitman, i, connected or pivoted to one of the crank-arms b.

It will be noticed that by the aforesaid arrangement of parts, in addition to obtaining a 65 long sweep or leverage, and consequently an increased reciprocation of the buckets, which accordingly increases the action of the drive-wheel, the chutes D are also reciprocated to cause them to operate in harmony with the 70 reciprocating buckets and alternately direct the water, which they receive from the stationary funnel E above, into the fixed longer chutes F below, arranged so as to conduct the water to the buckets at alternate intervals.

The water is received by the funnel E from 75 the flume or water source.

This device dispenses with all incasing or inclosing of the parts to serve as means for holding or conducting the water, and thus simplifies and forms a skeleton-machine, which 80 greatly lessens expense.

I am aware that it is old to effect the alternate supply or feeding of the water to fixed deflecting-chutes by a valve hung in a "neck" 85 of the chutes at their convergent ends.

By my construction and arrangement I dispense with the valve, substituting therefor and the fixed chutes reciprocating uniting chutes or funnels, by which I obtain increased lever- 90 age and power.

Having thus fully described my invention, I claim and desire to secure by Letters Patent—

In a hydraulic engine, the combination of 95 the upper set of reciprocating chutes, D D, disposed under the fixed funnel E and above the stationary chutes F, and having a crank-shaft, f f', connected by a short link, g, to a lever, h, with its longer arm connected to a pitman, i, 100 with the disk a, carrying the reciprocating buckets C, and its shaft B, provided with arms b, one connected to the pitman i and both to the pitmen c and driving-wheel B', substantially as and for the purpose set forth.

In testimony whereof I affix my signature in presence of two witnesses.

Witnesses: CUMBERLAND MASSIE.
